ABSTRACT OF THE DISCLOSURE

Adamantane hydrocarbons of the C_{10} — C_{30} range having at least one unsubstituted bridgehead position are admixed with fuming sulfuric acid (102—112% H_2SO_4 equivalent) at a temperature between the freezing point of the acid and 50° C. to effect dissolution and the mixture is then reacted with water to form bridgehead monoools corresponding to the starting hydrocarbons.

BACKGROUND OF THE INVENTION

This invention relates to the conversion of adamantane hydrocarbons of the C_{10} — C_{30} range to bridgehead monoools. The starting adamantane hydrocarbons include adamantane itself and alkyladamantanes having 1 to 4 open bridgehead positions. The product of the reaction is a monoool or alcohol corresponding to the starting hydrocarbon but having a hydroxyl substituent at one bridgehead position.

The adamantane nucleus has ten carbon atoms, four of which are bridgehead carbons that are equivalent to each other, as can be seen from the following typographical representation:

As shown, the bridgehead carbon atoms customarily are designated by the numerals 1, 3, 5 and 7, respectively.

The preparation of methyl- and/or ethyl-substituted adamantanes by the isomerization of tricyclic naphthalenes by means of an aluminum halide or $HF-BF_3$ catalyst has been described by several references including the following: Schneider U.S. Pat. No. 3,128,316, dated Apr. 7, 1964; Janoski and Moore U.S. Pat. No. 3,275,700, dated Sept. 27, 1966; Schleyer et al., Tetrahedron Letters No. 9, pp. 305—309 (1961); and Schneider et al., J. A. C. S., vol. 86, pp. 5365—5367 (1964). The isomerization products can have the methyl and/or ethyl groups attached to the adamantane nucleus at either bridgehead or non-bridgehead positions or both, although completion of the isomerization reaction favors bridgehead substitution. Examples of alkyladamantanes made by such isomerization are methyladamantanes, dimethyladamantanes, ethyladamantanes, methylethyladamantanes, dimethylethyladamantanes and trimethyladamantanes.

Preparations of adamantanes hydrocarbons having higher alkyl substituents have been described in the following references: Schneider U.S. Pat. No. 3,382,288, dated May 7, 1968; Spengler et al., Erdöl und Kohle-Erdgas-Petrochemie, vol. 15, pp. 702—707 (1962); and Hoek et al., 85 (1966), Recueil, 1045—1053.

Procedures for converting adamantane hydrocarbons to bridgehead hydroxy derivatives have been described in the prior art. Schneider U.S. Pat. No. 3,356,740, dated Dec. 5, 1967, discloses the conversion of alkyladamantanes to bridgehead alcohols by air oxidation using a soluble metallic organic salt as catalyst. In J. Org. Chem.,

2

vol. 26, pp. 2207—2212 (1961), the air oxidation of adamantane itself in the presence of a peroxide catalyst is described. Moore U.S. Pat. No. 3,383,424, dated May 14, 1968, shows the oxidation of adamantane and alkyladamantanes by means of chromic acid in aqueous acetic acid under conditions to produce either monoools or diols.

SUMMARY OF THE INVENTION

The present invention provides a different way for converting adamantane or higher adamantane hydrocarbons having one or more saturated hydrocarbon group or groups to corresponding bridgehead monoools. According to the invention, such adamantane hydrocarbons are readily converted to their monoools in unusually high yields merely by mixing the hydrocarbon with fuming sulfuric acid to bring the hydrocarbon into solution in the acid phase and then adding water to react with the solute material and form bridgehead monoool corresponding to the starting adamantane hydrocarbon. Yields in excess of 95% typically can be obtained.

DESCRIPTION

The process of the invention more particularly comprises:

- 25 (a) establishing an admixture consisting essentially of a saturated adamantane hydrocarbon of the C_{10} — C_{30} range having 1 to 4 unsubstituted bridgehead carbon atoms and fuming sulfuric acid having a strength corresponding to 102—112% H_2SO_4 equivalent by weight, the temperature of the admixture being between the freezing point of the acid and 50° C.;
- 30 (b) mixing the admixture at said temperature until at least a substantial proportion of the hydrocarbon has dissolved in the acid;
- 35 (c) and reacting the admixture with water to form a bridgehead monoool corresponding to the starting adamantane hydrocarbon.

The process appears to involve a carbonium ion reaction which can be illustrated by considering, for example, 40 the conversion of 1,3-dimethyladamantane (for convenience, DMA) to its corresponding alcohol, as follows (non-reacting hydrogen atoms being omitted for simplicity):

As illustrated by the equations the mechanism is visualized as involving the abstraction of a bridgehead hydrogen atom by means of the fuming sulfuric acid to form a DMA carbonium ion. While the hydrocarbon itself is not very soluble in the acid phase, the carbonium ion is and the hydrocarbon material thus becomes solubilized as mixing occurs in steps (a) and (b). When the mixture is then diluted with water, the water immediately reacts with the carbonium ion to form the desired bridgehead monoool. The latter precipitates and can be recovered from the aqueous acid by filtration.

The invention can be used to prepare bridgehead monoools from adamantane or any saturated adamantane hydrocarbon of the C_{11} — C_{30} range having one or more alkyl and/or cycloalkyl substituents provided that the nucleus has at least one unsubstituted bridgehead position. The alkyl or cycloalkyl substituents can be located at other bridgehead positions of the nucleus or at non-bridgehead positions or both, and such substituents are substantially unaffected at the relatively low temperatures and short

reaction times employed in the present process. The following are some specific examples of starting materials: adamantanane; 1-methyl or 2-methyladamantane; 1,2- 1,3- or 1,4-dimethyladamantane; 1- or 2-ethyladamantane; 1-ethyl-3-methyladamantane; 1-ethyl-3,5-dimethyladamantane; 1,3,5 - trimethyladamantane; nonbridgehead trimethyladamantanes; diethyladamantanes; 1 - n - propyl or 1-isopropyladamantane; 1-methyl - 2 - propyladamantane; 1 - n - butyladamantane; 1,3-di-n-pentyladamantane; 1-cyclopentyl or 1-cyclohexyladamantane; 1-methyl-3-heptyladamantane; 1-n-decyladamantane; 1-n-decyl-3-ethyladamantane; 1,3-dicyclohexyladamantane; 1 - n - hexadecyladamantane; 1,3,5 - dicyclopentyladamantane; 1-eicosyladamantane and the like. Other examples can be found in the references cited above.

The strength of the fuming sulfuric acid used in the process should be in the range of 102-112% H_2SO_4 equivalent by weight and preferably 103-108% H_2SO_4 equivalent. Preferably enough fuming acid is used to provide at least two moles of SO_3 per mole of the starting adamantanane hydrocarbon and more preferably an amount substantially in excess of such proportion is employed. On a volume basis, proportions generally used are in the range of 1:1 to 10:1 volumes of the fuming acid per volume of adamantanane hydrocarbon.

The reaction of steps (a) and (b) as shown in the foregoing equation is carried out at relatively low temperature and the reaction time preferably is minimized to prevent the formation of substantial amounts of by-products. The temperature employed is between the freezing point of the fuming acid (circa 8-10° C.) and 50° C. and preferably is in the lower part of this range, e.g. below 25° C.

When the adamantanane hydrocarbon and the fuming acid are first admixed, a two-phase system is formed since the hydrocarbon itself has a relatively low solubility in the acid. However the hydrocarbon material becomes solubilized in the acid as it converts to the carbonium ion form, and this conversion will cause all of it to go into solution if sufficient mixing time is allowed. Mixing of the admixture is carried out until at least a substantial proportion of the adamantanane hydrocarbon has dissolved in the acid and preferably until substantially all of it has dissolved. In order to minimize by-product formation, water is then immediately added to react as shown for step (c), whereupon all of the material of carbonium ion form is converted to the corresponding monool. On the other hand, if the solubilized material is allowed to stand for a time before the water is added, the chances of forming undesired by-products are increased since the carbonium ion material may be capable of undergoing reactions leading to other products.

In order to minimize the time in steps (a) and (b), vigorous mixing is advantageous so as to effect good contact between the phases. This reduces the time necessary for bringing the hydrocarbon material into solution in the acid phase. The rate at which dissolution occurs will vary depending upon the particular adamantanane hydrocarbon used as feed. The adamantanane hydrocarbons which are solids at the reaction temperature employed, such as adamantanane or 1-methyladamantane, tend to become solubilized more slowly than the liquid alkyladamantanes, such as 2-methyladamantane, 1- or 2-ethyladamantane, any of the dimethyladamantanes, ethylmethyladamantanes, trimethyladamantanes, or tetramethyladamantane having one or more nonbridgehead methyl groups. Also, as the molecular weight of the feed hydrocarbon is increased, the rate of dissolution in the fuming acid tends to decrease and longer mixing times are required to effect complete solution. In cases when a normally solid adamantanane hydrocarbon is used as feed, it is advantageous to add it to the acid in the form of finely divided powder to facilitate solubilization.

As soon as all or at least a substantial amount of the feed hydrocarbon has dissolved in the fuming acid, the

reaction mixture is admixed with cold water or ice to effect the reaction of step (c). This should be done with adequate cooling to prevent an inordinate rise in temperature. The proportion of water added should be sufficient to reduce the acid strength to less than 60% H_2SO_4 and, if desired, to considerably less than this level. Dilution of the mixture in this manner causes immediate formation of the monool which is insoluble in the aqueous acid and precipitates. The resulting alcohol can be recovered by filtration and then can be purified by recrystallization from a suitable solvent such as pentane, hexane or petroleum ether. Based on the adamantanane hydrocarbon consumed, yields above 95% generally can be obtained, particularly if low reaction temperatures (e.g., 10-20° C.) are used.

The following examples are specific illustrations of the invention:

Example I

This example shows the conversion of 1,3-dimethyladamantanane (DMA) to the corresponding bridgehead alcohol. 100 ml. of 20% fuming sulfuric acid (104.5% H_2SO_4 equivalent) were cooled to a temperature of about 10° C. by immersion in an ice bath, 10 g. of DMA (M.P. = -30° C.) were added thereto and the mixture was then rapidly stirred at about 10° C. for approximately 5 minutes, by which time almost all of the DMA had gone into solution. The mixture was poured over a relatively large volume of ice, the thus diluted mixture was extracted with diethyl ether and the ether was evaporated. The resulting crude product upon analysis by VPC showed the following composition:

	Percent
1-hydroxy DMA	96.5
Unreacted DMA	1.8
By-products	1.7

This product was recrystallized from petroleum ether and 1-hydroxy-3,5-dimethyladamantanane having a melting point of about 97° C. was obtained. The yield was >95%.

Example II

In this example the starting hydrocarbon was 1-ethyl-3,5-dimethyladamantanane (EDMA) which melts below -80° C. The reaction was run under the same conditions as described in Example I except that the time of mixing was increased to 10 minutes. The crude product obtained by analysis of the ether extract had the following composition:

	Percent
1-hydroxy-EDMA	81.8
Unreacted EDMA	17.0
By-products	1.2

Upon purification of the product by recrystallization from petroleum ether, 1-hydroxy-EDMA was obtained having a melting point of about 85° C. The yield of this monool was about 98.5% based on EDMA consumed.

Comparison of Example II with Example I indicates that the rate of dissolution of the liquid adamantanane hydrocarbons in the fuming acid increases as the hydrocarbon molecular weight increases.

Example III

Example II was repeated except that adamantanane was substituted for EDMA, the solid adamantanane being added to the fuming acid as a powder. It was found that in the 10 minutes reaction time allowed only 10% of the adamantanane was converted to 1-adamantanol. This was due to the slower rate of dissolution of the solid adamantanane in the fuming acid; most of the adamantanane had not gone into solution during the time permitted. Essentially no reaction products other than 1-adamantanol were formed.

When other adamantanane hydrocarbons as herein specified are substituted for those used in the foregoing exam-

5
ples, analogous results are obtained. However, in view of the decrease in rate of dissolution as the molecular weight of the adamantane hydrocarbon feed increases, as shown by comparing Examples I and II, and in further view of the fact that lower molecular weight adamantane hydrocarbons are generally more readily available, the invention will have its most utility in the conversion of adamantanes of the C₁₀–C₂₀ range.

The use of other acid strengths and other temperatures within the limits herein described also results in effective conversion of the specified adamantane hydrocarbons to the corresponding bridgehead monoools.

The invention claimed is:

1. Method of converting adamantane hydrocarbons to bridgehead monoools which comprises:
  - (a) establishing an admixture consisting essentially of a saturated adamantane hydrocarbon of the C₁₀–C₂₀ range having 1 to 4 unsubstituted bridgehead carbon atoms and fuming sulfuric acid having a strength corresponding to 102–112% H₂SO₄ equivalent by weight, the temperature of the admixture being between the freezing point of the acid and 50° C.;
  - (b) mixing the admixture at said temperature until at least a substantial proportion of the hydrocarbon has dissolved in the acid;
  - (c) and reacting the admixture with water to form a bridgehead monoool corresponding to the starting adamantane hydrocarbon.
2. Method according to claim 1 wherein the temperature is less than 25° C.
3. Method according to claim 2 wherein said strength corresponds to 103–108% H₂SO₄.
4. Method according to claim 1 wherein said strength corresponds to 103–108% H₂SO₄.
5. Method according to claim 1 wherein said adamantane hydrocarbon is of the C₁₀–C₂₀ range.
6. Method according to claim 5 wherein the starting adamantane hydrocarbon is selected from the group consisting of adamantane, methyladamantanes, dimethyladamantanes, ethyladamantanes, methylethyladamantanes, dimethylethyladamantanes and trimethyladamantanes.
7. Method according to claim 6 wherein said strength corresponds to 103–108% H₂SO₄ and the temperature is less than 25° C.
8. Method according to claim 5 wherein said strength corresponds to 103–108% H₂SO₄ and the temperature is less than 25° C.

9. Method according to claim 1 wherein said adamantane hydrocarbon is a C₁₁–C₂₀ alkyladamantane, the mixing thereof with said acid in step (b) is continued until substantially all of the adamantane hydrocarbon has dissolved in the acid, and the admixture is then reacted with water before substantial by-product formation can occur.

10. Method according to claim 9 wherein said strength corresponds to 103–108% H₂SO₄ and the temperature is less than 25° C.

11. Method according to claim 10 wherein the starting adamantane hydrocarbon is selected from the group consisting of adamantane, methyladamantanes, dimethyladamantanes, ethyladamantanes, methylethyladamantanes, dimethylethyladamantanes, and trimethyladamantanes.

12. Method according to claim 11 wherein the starting adamantane hydrocarbon is 1,3-dimethyladamantane; 1-ethyladamantane; 1-ethyl-3-methyladamantane; 1,3,5-trimethyladamantane or 1-ethyl - 3,5 - dimethyladamantane.

13. Method according to claim 1 wherein the starting adamantane hydrocarbon is 1,3-dimethyladamantane; 1-ethyladamantane; 1-ethyl-3-methyladamantane; 1,3,5-trimethyladamantane or 1-ethyl - 3,5 - dimethyladamantane.

14. Method according to claim 13 wherein the temperature is less than 25° C., said strength corresponds to 103–108% H₂SO₄, the mixing in step (b) is continued until substantially all of the adamantane hydrocarbon has dissolved in the acid, and the admixture is then reacted with water before substantial byproduct formation can occur.
